Patented Dec. 16, 1913.

UNITED STATES PATENT OFFICE.

WICKLIFF M. BROADY, OF BROADWATER, NEBRASKA.

WEED-CUTTER.

1,081,658.

Specification of Letters Patent. Patented Dec. 16, 1913.

Application filed August 6, 1912. Serial No. 713,653.

To all whom it may concern:

Be it known that I, WICKLIFF M. BROADY, a citizen of the United States, residing at Broadwater, in the county of Morrill and 5 State of Nebraska, have invented certain new and useful Improvements in Weed-Cutters, of which the following is a specification.

This invention is a device for removing 10 weeds and similar growths from the space alongside railroad tracks and from between the rails of the tracks.

The invention seeks to provide a device which may be readily attached to a hand car, 15 railroad velocipede, or similar vehicle and easily manipulated to project from the track rail so as to cut down the vegetable growths as the vehicle moves over the track.

The objects of the invention are attained 20 in such a device as is illustrated in the accompanying drawings, and the invention consists in certain novel features which will be hereinafter first fully described and then more particularly pointed out in the appended claims.

In the drawings: Figure 1 is a perspective view of my improved device in its operative position upon a hand car; Fig. 2 is a detail perspective view of a socket which constitutes a guide for the device as it is moved 30 along the track rails; Fig. 3 is a central detail vertical section of the socket shown in Fig. 2; Fig. 4 is a detail perspective view of the blade or cutter.

In carrying out my invention, I pivotally attach to the hand car or other vehicle 1, at the rear end thereof, a blade-carrying arm 2, the upper end of which projects up to within convenient reach of the operator 35 upon the hand car, while the lower end thereof is adapted to extend down to the track rail 3, as clearly shown. The lower end of the said arm is beveled, as indicated at 4, and around said lower beveled end is secured a socket 5 having a depending lip or flange 6 which is adapted to engage the side of the track rail and thereby guide the device as the vehicle travels. To the side 45 of the blade-carrying arm, near the lower end of the same, I secure the upturned end 7 of a blade 8 which may be of any stout light material, preferably metal, and is adapted to project laterally from the arm below the tread of the rail, so that, as the 50 vehicle travels over the track, the blade will

be drawn forcibly against the upstanding weeds and other plants and thereby cut down the same so that the track will be freed of the obnoxious vegetation which tends to clog the wheels of the cars and also 60 to make the tracks slippery so that accidents are liable to occur.

My device is exceedingly simple in its construction and may be applied at a trifling cost and will be found thoroughly efficient 65 in use. The blade may be easily bent or stamped out of a piece of sheet metal and will be used between the rails as well as at the side of the track. The upturned end 7 of the blade furnishes a secure support for 70 the blade, while the intermediate portion 9 is bent outwardly and downwardly so as to clear the track rail and thereby bring the blade proper close to the road bed. When the vehicle is traveling over a clear, clean 75 stretch of road, the upper end of the arm may be easily depressed and the blade thus raised to an inoperative position and, consequently, wear upon the device will be reduced to a minimum. 80

The blade-carrying arm may be attached at either end of the hand-car or other vehicle and in Fig. 1 of the drawings I have shown an arm at one side of the car having its blade arranged to cut the weeds at the 85 side of the track and an arm at the other side of the car having its blade arranged to cut the weeds between the track rails, the latter arm being illustrated in its raised inoperative position. It will be readily understood that either arm may be raised or lowered independently of the other or that both cutters may be used at the same time. When the cutters are provided at both sides of the car, as illustrated, the car may be run 90 in one direction over a short stretch of the road so as to destroy the weeds at one side of each track rail and then run back in the opposite direction, after being reversed, to destroy the weeds at the opposite sides of 95 the track rails. The depending guide lip 6, as shown most clearly in Fig. 3, bears against the side of the head of the track rail so that the device may be more easily held in proper position upon the rail and the 100 tendency of the blade to swing rearwardly when encountering large, thick, or tough weeds or other plants will be effectually resisted. Moreover, this lip by riding closely 105 against the side of the rail head removes 110

therefrom all particles of cut stems or leaves which may tend to adhere thereto so as to create a slippery condition of the tracks.

What I claim is:

- 5 1. A railway weed cutter comprising in combination with a car a blade-carrying arm mounted on the car, a track-engaging lip depending from the lower end of said arm, and a blade secured to and projecting laterally from the said arm near the lower end thereof.
- 10 2. A railway weed cutter comprising in

combination with a car a blade-carrying arm mounted on the car, a socket secured around the lower end of said arm and having a depending track-engaging guiding lip, and a blade secured to said arm near the lower end thereof and projecting laterally therefrom. 15

In testimony whereof I affix my signature in presence of two witnesses.

WICKLIFF M. BROADY. [L. s.]

Witnesses:

J. E. WHEELER,
